UNITED STATES PATENT OFFICE.

EDWIN W. ANDREWS, OF BUFFALO, NEW YORK, ASSIGNOR TO JOHN JEPSON AND EMMA U. ANDREWS, TRUSTEES, BOTH OF BUFFALO, NEW YORK.

INCUBATOR.

1,073,314.

Specification of Letters Patent. Patented Sept. 16, 1913.

Application filed October 21, 1911. Serial No. 655,885.

To all whom it may concern:

Be it known that I, EDWIN W. ANDREWS, a citizen of the United States, residing at Buffalo, in the county of Erie and State of New York, have invented a new and useful Incubator, of which the following is a specification.

My invention relates to incubators.

The objects of this invention are to provide improved means for regulating the heat and moisture which are supplied to the incubating chamber.

These several features will be evident from the following specification and the accompanying drawings, in which,—

Figure 1 is a front elevation; Fig. 2 is a longitudinal central section; Fig. 3 is a plan of the water and air circulation; Fig. 4 is an enlarged section of my heater and lamp burner; Fig. 5 is a section on the line $x-x$ of Fig. 4; Fig. 6 is a plan of my lamp burner on an enlarged scale, showing the flame-control apparatus; Fig. 7 is a detail in plan of my egg-tray; and Fig. 8 is a section on the line $y-y$ of Fig. 7.

Water circulation.—In this type of apparatus the heating of the incubator chamber is effected by hot water circulation. Referring to Figs. 1 to 4, 1 is a water heater hereinafter more fully described. From near the top of this heater a pipe 2 leads to a pipe 3, which leads to the parallel pipes 4 and 5, which lead to the closed heating tray 6, which leads to the parallel pipes 7 and 8, which lead to the pipe 9, which leads to the parallel pipes 10 and 11, which lead to the heating tray 12, which leads to the parallel pipes 13 and 14, which lead to the pipe 15, which leads to the pipe 16, which passes downwardly and enters the heater 1 near the bottom, as shown in Fig. 2. It will be seen that the piping is disposed near the top of the chamber and adjacent to the inner upper angles. This arrangement secures the most uniform heating of the chamber.

Air circulation.—Adjacent to both ends of the chamber are air flues 17, 18, 19, 20, 21, 22. The flue 17 is an air heating flue; the others are ventilating flues. Air enters the flue 17 from atmosphere through holes 23, is heated by the pipes 2 and 16 which pass through this flue, and passes into the chamber through holes 24 near the top of the flue. Each of the flues 18, 19, 20, 21, 22 has holes 25 near the bottom leading from the

incubating chamber, as clearly shown with reference to the flue 21 in Fig. 2; and holes near the tops of these flues permit the foul air to pass out. It will thus be seen that fresh air is taken in, warmed and discharged into the upper part of the chamber, where it is rapidly disseminated by the action of the heating pipes. The foul air, on the other hand, is drawn off at the bottom of the chamber from several different points by separate flues, thus insuring a uniform purity of air in the brooding area of the chamber.

Thermostatic control.—My improved thermostatic device is shown in Fig. 2. It comprises a bell-crank lever 27, pivoted to a bracket-bearing 28 secured to one wall of the chamber. To the short arm of this lever 27 is secured a rod 29, which is made of a metal having a large coefficient of expansion, and which passes out through the opposite walls and is provided with an adjusting-nut 30. Pivoted to the long arm of the lever 27 is a rod 31. The upper end of this rod is adjustably secured to a bar 32, which is centrally pivoted to the top of the incubator. One end of this bar 32 is adjustably connected to a rod 34 which, at its other end, is connected to the lamp control device presently described. The opposite or inner end of the bar 32 connects with a rod 35 which governs the moisture regulator, also presently described. It will be seen that the weight of the long arm of the bell-crank lever tends to hold the parts in the closed position, that is, the position in which the minimum heat is applied and the minimum moisture supplied; and it will be seen that I depend entirely upon the gravity action of the bell-crank lever and the expansion and contraction of the thermostatic rod, thus dispensing with all springs or weights.

Moisture regulator.—Experience extending over a period of nearly thirty years has taught me that, in the incubation process, the maximum of heat requires the maximum of moisture supply; that as the temperature rises the moisture should be increased, and vice versa. To secure proper supply and control of moisture has been a difficult problem, and is an important feature of my present invention. Referring to Figs. 2 and 3, within the heating tray 12 is a metal cylinder 36, secured water tight to the bottom of the tray, and open at both ends—the upper

end being above the water level and the lower end extending slightly below the bottom of the tray 12. Steam generated in the tray 12 may, therefore, pass down through the cylinder 36 into the incubating chamber. A rod 35 adjustably secured to the inner arm of the bar 32 passes down through the top of the incubator and through the cylinder 36. Secured to its lower end is a disk 37, of the proper size to cover the lower end of the cylinder 36. When thermostatic action rocks the bar 32, the disk 31 is lowered away from or raised toward the cylinder 36, thus regulating the volume of steam passing from the tray into the chamber directly with the variation in temperature.

Lamp flame government.—Referring especially to Figs. 4 and 6, my improvement in lamp flame governing device consists of a metal sleeve 38 which fits freely over the wick-tube of the burner. Secured to the opposite rounded sides of the sleeve 38 are ears 39. A wire 40 is pivotally connected to the rod 34 (see Figs. 1 and 2), is bent at right angles at 41 (Fig. 6), passes through the flange of the burner at the rear of the wick-tube, then is bent forward at right angles and passes through one of the ears 39, then is bent at right angles to lie parallel to, but clear of, the sides of the sleeve 38, then bent at right angles to pass through the second ear 39, then bent at right angles to pass through the flange of the burner again. When the rod 34 is raised by thermostatic action, this wire will lift the sleeve 38 by the ears 39 and raise it above the wick-tube. This has the same effect upon the flame as turning the wick down. Reverse action lowers the sleeve and increases the flame.

Heating device.—Referring to Figs. 2, 4 and 5, my improved heating device comprises a water-containing chamber 1 with which the pipes 2 and 16 connect. This chamber is provided with an opening at the top for filling and with a cap. Extending upwardly within the water chamber is the lamp chimney 43. This extends to a point near the top of the water chamber, but below the water level, is closed at the top, and adjacent to its top are two flues 44, 45, which pass through the water chamber and open to atmosphere. This construction secures large economy of fuel, and prevents undue heating of the chimney or burner.

Egg-tray improvement.—The egg-tray shown in Figs. 7 and 8 is, in general, the ordinary construction—consisting of a frame, division strips 46 and wire screen 47. But heretofore it has been necessary to leave one division open in part (and without eggs, of course) in order that the chicks may drop down into the brooder area of the chamber.

This necessarily decreased the egg capacity of the tray by the amount of such opening. In any setting of eggs a small number will be found sterile, and will be removed from time to time—generally a number equal to the space heretofore left for an opening for the chicks. My improvement consists of a thin wood slide 48 which forms a flooring for a part of one section of the tray. This slide lies just below the plane of the wire screen 47, and slides in slots in the cleats 49, as clearly shown in Fig. 8. The wire screen is cut away over this slide. The tray is entirely filled with eggs, including the area of the slide 48. As the incubation process goes on and sterile eggs are found and removed, those resting upon the slide 48 are removed to the places made vacant by the sterile eggs; so that, by the time the hatching period arrives, the slide 48 may be moved back under the wire, thus providing an opening for the chicks to go down into the brooder area. This improvement gives a substantial increase of egg capacity in any given tray.

Having thus described my invention, what I claim is:

1. An incubator comprising an incubating chamber, a hot water heating system having a conduit arranged in the incubating chamber and provided in the upper part of its vapor space with a vent adapted to place the interior of said conduit in communication with the interior of the incubating chamber, a movable cover for said vent, a thermostat arranged in the incubating chamber, and means operatively connecting the thermostat with said cover so as to open the vent as the temperature rises and to close the vent as the temperature drops.

2. An incubator comprising an incubating chamber, a hot water circulation system having a tray and a vent in said tray for emitting moisture into said chamber, a cover for said vent, a thermostat comprising a bell-crank lever pivoted on one part of said chamber, an expansible rod pivoted to one arm of said lever and adjustably mounted on another part of said chamber, a bar pivoted on the upper part of said chamber, a rod connecting said bar with the other arm of said bell-crank lever, a heating device, means for controlling said heating device comprising a rod connecting with said bar, and a rod connecting said cover with said thermostat for opening and closing said vent.

In testimony whereof I have hereunto set my hand in the presence of two witnesses.

EDWIN W. ANDREWS.
